Howard M. Cohn

(57) **CLAIM**

The ornamental design for a downspout diverter as shown and described.

DESCRIPTION

FIG. 1 is a perspective view of a downspout diverter showing my new design;

FIG. 2 is a top perspective view thereof;

FIG. 3 is a bottom perspective view;

FIG. 4 is a front view thereof;

FIG. 5 is a back view thereof;

FIG. 6 is a left view thereof;

FIG. 7 is a right view thereof;

FIG. 8 is a bottom plan view thereof;

FIG. 9 is top plan view thereof; and,

FIG. 10 is a perspective view of a downspout diverter shown in a state of use.

The broken lines illustrate portions of the downspout diverter that form no part of the claimed design.

1 Claim, 10 Drawing Sheets
